CIRCULAR-KNITTING MACHINE.

Application filed October 19, 1925, Serial No. 63,517, and in Great Britain October 25, 1924.

This invention relates to circular knitting machines and has reference to splicing mechanism by which a re-inforcing thread or yarn is supplied and fed along with the main yarn, to strengthen the fabric, the splicing thread end being held by a trapper when splicing is discontinued. Such mechanism frequently comprises a take-up lever having a yarn-guiding free end for use in the knitting of heel and toe pouches, where a loose thread is laid round the temporarily inactive needles of the needle cylinder during the reciprocation of the machine for heel and toe knitting, the function of the (spring controlled) take-up lever being to take up the slack thread and keep it taut as it unwinds from those needles which have been rendered inactive just prior to and during reciprocation.

The take-up lever at its outer or free guide end must exert just sufficient pull on the yarn to take up the slack thread the whole time the pouch is knitted, but it is the common practice to depress this said lever by any suitable means after the pouch is made so that no tension whatever is left upon the supply yarn while uniform tubular fabric is knitted, and as the take-up lever, at the finish of the pouch, is acting upon a thread that would otherwise be slack, this lever cannot be depressed until the machine resumes its rotary motion.

The placing of this take-up lever out of tensional contact with the supply thread being the last phase of the splicing operation, it is usually the first to be released into its active capacity and this occurs before the end of the splicing thread, now free by reason of the trapper opening and releasing the same, has reached and passed over the operative or guide end of the take-up lever. Consequently the splicing thread instead of adhering closely to the main supply yarn and being carried therewith over the take-up lever guide end, gets below the said guide end and is likely to become separated from the main supply yarn. It is an object of the present invention to overcome this defect.

According to the present invention a cir-

cular knitting machine is provided with a take-up which normally is inactive but which is rendered active to take up slack in the yarn when a re-inforcing or other second thread or yarn is to be supplied to the needles, and means to bring the take-up into action, said means comprising controlling mechanism which is definitely timed to delay the release of the take-up until after the end of the said second thread or yarn shall have been fed to and knitted into the fabric.

Another feature of the invention is a circular knitting machine having a splicing mechanism comprising a trough or like member for pressing a reinforcing or other second thread or yarn against the main yarn so that it travels therewith, combined with a trapper for the said second yarn which trapper is located between the inner end of the trough and the needle cylinder in close proximity to the needles.

The above and other features of the invention will be apparent to those skilled in the art from the following description of one form of the invention which is illustrated in the accompanying drawings in which—

Figure 1 is an elevation showing, somewhat diagrammatically, sufficient of the parts of a knitting machine to enable the invention to be understood;

Figure 2 is a view of certain of the parts shown in Figure 1 but looking in the direction indicated by the arrow in that figure.

As usual the main supply yarn 6 is fed downwards at an oblique angle and the splicing yarn 4 lies in a horizontal position along the bottom of the groove in a trough 3, which may be of the same general nature as the trough described in the specification of our prior British Letters Patent No. 220,248.

In the present construction, however, there is situated between the inner end of the trough and the needle cylinder and in close proximity to the needles a trapper 5 shown as carried by a lever 31 and controlled by a spring 7 which tends to keep it in its closed or gripping position.

The splicing mechanism in this construction provides for an independent control of

the take-up lever 9 to enable its release to take place after the splicing thread 4 has been carried to the needles, the release of the take-up lever being effected by a movement 5 of the control drum 11 subsequent to that which put the splicer into action.

A convenient arrangement for this is as follows: A catch 13, shown as a lever-catch, governs both the locking and the release 10 of the take-up lever 9 through the co-operation of the post lever or member 15 carrying with it pins or studs 17 and 19 suitably placed to engage with the lever catch 13 at regulated positions. The member 15 turns about the 15 same centre 14 as that about which the catch 13 turns. Further, there is provided a stepped cam 21 on the control drum 11, the member 15 being operated either direct from the stepped cam 21 or as shown through the 20 medium of a two-armed lever 23, to which it is connected by a link 24, so that as the control drum 11 is advanced by intermittent stages the stepped cam 21 actuates the member 15 causing it to take a higher or lower 25 level.

The end of the lever-catch 13 is provided with a cam incline 25 and with a slight return cam incline or slot 27 which engages with a pin 29 on a downwardly extending 30 part 26 of the take-up lever 9 when the member 15 is at its lowest or normal position that is to say, when the stepped cam 21 on the control drum 11 has been moved away from under the lever 23.

35 The splicing mechanism thus completes its function in sequential stages governed by the stepped cam 21 on the control drum 11 in the following order:—

The first rise of the stepped cam 21 lifts 40 the member 15 to a height to bring the splicer trough 3 (and consequently the splicer thread) pressed well on to the main supply yarn 6, following which at the end of this first movement of the stepped cam, the trap- 45 per 5 is opened by its lever 31 engaging with a pin or projection 33 on the lever 23. The second rise of the stepped cam by a further advance of the control drum 11 now causes the member 15 to lift to another height where 50 the pin 17 thereon makes contact with the lever catch 13 and releases the take-up lever 9 at the moment the machine starts to reciprocate, that is when the splicing thread 4, having been carried along with the main yarn 6, has already been knitted by some of the needles. A third rise of the stepped cam by 55 a third advance of the control drum allows part of the splicing mechanism to fall (as explained in the specification before men- 60 tioned) to a position at which the yarn 6 and the splicing thread 4 continue to feed to the needles but are well separated from each other prior to the closing of the trapper 5 on the splicing thread to break off and dis- 65 continue the supply of the splicing thread

at the fourth movement of the control drum causing a step down 35 of the stepped cam 21 to act upon the lever 23. A fifth advance of the control drum moves the stepped cam clear of the lever 23 which then resumes its 70 lowest or normal position and by so doing the pin 19 on the member 15 engages the lever-catch 13 to bring the incline 25 at its free or outer end into operative contact with the pin 29 on the take-up lever 9 to depress the said lever and then hold it securely 75 locked in its depressed position to relieve the main yarn 6 of any further tension until the splicing mechanism has again been put in action.

Such a timed latching and unlatching mechanism for the take-up, by reason of its assuring automatically an adequate delay in the coming into action of the take-up until after the splicing mechanism has actually fed 80 the splicing thread to the needles, considerably reduces any tendency to imperfect splicing and the consequent production of faulty goods particularly in the case of high speed 85 circular knitting machines.

It is to be understood that although a "reinforcing" thread or yarn is hereinbefore referred to, such term must not be regarded as a limitation as obviously any usual second 90 yarn which is to be introduced into the fabric during the knitting operation can be dealt with by mechanism according to the invention.

We claim:

1. In a circular knitting machine, in combination, a pivoted member for pressing a second yarn into frictional engagement with the main yarn so that it is fed therewith, a normally inactive take-up, a pivoted actuating member operatively connected with the aforesaid pivoted member, a lever catch mounted on the pivot of said actuating member to govern both the locking and the release of the take-up, means to cause the lever catch to engage and disengage the take-up lever, 100 operative connections including a series of levers and links between said actuating member and a stepped cam, a pivoted trapper for the second yarn, and an operative connection between said pivoted trapper and one of the 105 last mentioned levers substantially as set forth.

2. In a circular knitting machine, the combination with a shiftable member for pressing a splicing yarn and a main yarn into engagement, of a normally inactive takeup, a lever for operating said takeup, said lever directly engaging said presser for operating the latter, and timing means operating through said lever to shift said presser and 110 to place said takeup in operative position after the main and second yarns have been fed to the fabric.

3. In a circular knitting machine, the combination with a shiftable member for press- 115

ing a splicing yarn and a main yarn into engagement, of a normally inactive takeup, a lever for operating said takeup, said lever directly engaging said presser for operating 5 the latter, a cam, and means operated by said cam and acting through said lever to shift said presser and to place said takeup in oper-

ative position after the main and second yarns have been fed to the fabric.

In testimony whereof we have signed our 10 names to this specification.
